UNITED STATES PATENT OFFICE

BURTON S. FLORADAY, OF TOLEDO, OHIO, ASSIGNOR, BY MESNE ASSIGNMENTS, TO THE DURA COMPANY, OF TOLEDO, OHIO, A CORPORATION OF OHIO

MANUFACTURE OF WINDOW REGULATORS

Application filed December 27, 1927. Serial No. 242,950.

The invention relates to the manufacture of lifter elements for window regulators and one of the objects of the invention is to so construct the parts of the lifter element that they may be economically manufactured and assembled to form a strong and substantial unit. Another object is the manufacture of the gear segments with the minimum loss of material and with the minimum cost. With these as well as other objects in view, the invention resides in the novel features of construction and combinations and arrangements of parts as more fully hereinafter set forth.

15 In the drawings:—

Figure 1 is a side elevation of a window regulator lifter element comprising a gear segment and a lifter arm;

Figure 2 is a bottom view thereof;

20 Figure 3 is a plan view of the blank from which the gear segments are formed and showing the lines of severing.

As shown in Figures 1 and 2, the lifter element comprises the lifter arm 1 and the gear segment 2, the arm being adapted to be connected at its outer end to the window and the gear segment being secured to the lifter arm and being adapted to mesh with the driving pinion of the window regulator. The gear segment is formed of a sheet metal arcuate rack having the arcuate series of teeth 3 at its outer periphery for meshing with the teeth of the driving pinion and the diametrically opposite anchoring portions 4 at its ends. This rack is crescent-shaped, it having a depth which progressively increases from its ends to its center so that flexing or bending of the rack when in operation is avoided. The lifter arm is also formed of sheet metal and extends at one side of the gear segment and is rigidly connected to the anchoring portions 4 by suitable means such as the rivets 5. The central portion 6 of the lifter arm intermediate the anchoring portions is inwardly offset to extend in the plane of the gear segment, this central portion having the aperture 7 through which extends the pivot for the lifter element, the arrangement being such that tendency of the lifter element being

tilted by driving of the gear segment through the driving pinion is minimized.

To economically manufacture the gear segment 2, I provide the sheet metal blank 8, preferably having a width equal to the length 55 of the gear segment, which is determined by the distance between the ends 9 of the anchoring portions 4. This blank is then progressively fed longitudinally through a suitable machine having a reciprocable punch which 60 severs the blank progressively into a series of gear segments with one nesting within another and a part of the toothed outer periphery of the one coinciding with the inner periphery of that immediately in advance, the 65 metallic pieces 10 between the anchoring portions 4 of the successive gear segments being scrapped.

With this method, it will be seen that but 70 very little metal is wasted and that the gear segments are formed with the minimum of time, inasmuch as the lines of severing therebetween coincide with the tooth contours. It will be furthermore seen that with this method the gear segments are formed with 75 depths which progressively increase from their ends to their centers. With this construction the gear segments may be quickly and economically secured to the lifter arms and form lifter elements of strong and sub- 80 substantial construction.

What I claim as my invention is:

1. In the manufacture of gear segments, each having a peripheral arcuate series of teeth, that step which consists in severing a 85 blank into like gear segments the outer periphery of one segment coinciding substantially its entire length with the inner periphery of the adjacent segment.

2. In the manufacture of window regulator gear segments, that step which consists in severing a blank into like arcuate racks with one nesting within another. 90

3. In the manufacture of window regulator gear segments, each having an arcuate 95 series of teeth at its outer periphery, that step which consists in severing a blank into like gear segments, part of the outer periphery of one coinciding with the inner periphery of another. 100

4. In the manufacture of window regulator gear segments, each having an arcuate series of teeth at the outer periphery, that step which consists in severing a blank to form the arcuate series of teeth and simultaneously the inner periphery of an adjacent gear segment.

5. In the manufacture of a window regulator, the severing of a blank into like gear segments with one nesting within another and each having anchoring portions at its ends, and the securing of a lifter arm to the anchoring portions of each gear segment.

6. In the manufacture of a window regulator, the severing of a blank into like gear segments, each having anchoring portions at its ends and the securing of a lifter arm to the anchoring portions of each gear.

7. In the manufacture of a window regulator, the severing of a blank into like crescent shaped gear segments each having an outer arcuate series of teeth at the outer periphery, each having anchoring portions at its ends, and the securing of a lifter arm to the anchoring portions of each gear.

In testimony whereof I affix my signature.
BURTON S. FLORADAY.
